UNITED STATES PATENT OFFICE.

CHARLES B. ASKEW, OF CHICAGO, ILLINOIS.

INTERNAL-COMBUSTION ENGINE.

1,189,338.

Specification of Letters Patent.

Patented July 4, 1916.

Application filed March 13, 1916. Serial No. 83,734.

To all whom it may concern:

Be it known that I, CHARLES B. ASKEW, a citizen of the United States, residing at Chicago, in the county of Cook and State of Illinois, have invented certain new and useful Improvements in Internal-Combustion Engines, of which the following is a specification.

This invention relates to internal combustion engines and more particularly to means for supplying a combustible charge for utilization in such engines.

The most commonly used method of supplying a combustible mixture to a gas engine is to employ a carbureter, or what is sometimes termed a mixing valve, in which a readily vaporized hydro-carbon fuel is mixed with a moving column of air, the movement of air and fuel being induced by the vacuum tendency incident to the suction or downstroke of the engine piston. In systems of this sort it has been found impractical to use fluids other than comparatively light hydro-carbon oils which readily vaporize at normal temperatures, such for example as the distillate commonly known as gasoline. These lighter oils, such as gasoline, are the products of continued distillations of the natural crude mineral oils. Because of the cost of the process through which the crude oil must pass in reaching the degree of refinement necessary for utilization in carbureters of the common type, and the enormous demands for such oils, its market price is necessarily high. Hydro-carbon oils of lower grade are much more difficult to vaporize, but are correspondingly lower in cost, since they require a less degree of refinement. These lower grades of hydro-carbon oils are heavier than gasoline, and for use in the usual form of carbureter would require the addition of considerable heat to permit vaporization.

It is the purpose of my invention to provide an apparatus which will permit the utilization in gas engines of the heavier, less expensive grades of oil, such as kerosene, and others, having still less susceptibility to vaporization.

In its general aspects my invention comprises an apparatus for supplying under pressure a combustible liquid, such as hydro-carbon oil, either of a heavy grade, or of heavy grade mixed with a lighter grade, through an atomizing nozzle which is positioned to project the spray into the intake

duct of an internal combustion engine, the supply apparatus being proportioned to supply for each engine power stroke the maximum fuel content which the engine cylinder 60 is capable of utilizing when developing its maximum power, variation of power, or throttling of the engine being secured by varying the proportion of the spray projected into the intake duct. 65

A further object of my invention is to provide an apparatus adapted to handle without alterations either a light, readily vaporized oil, a heavy, less easily vaporized oil, or a mixture of both, thus enabling the 70 operator to readily start the engine in extremely cold weather and to operate the engine on either grade of fuel when the other grade is not available for supply.

Still other objects will become apparent 75 to those skilled in the art from a consideration of the following description and drawing, wherein:

Figure 1 is a side elevation of a diagrammatic layout of my apparatus shown in connection with a four cylinder gasoline automobile engine. Fig. 2 is a vertical diametric sectional view through the vaporizing chamber of the apparatus showing its connection to the intake pipe of a gas engine. 80 Fig. 3 is a sectional view on the line 3-3 of Fig. 2. Fig. 4 is a transverse sectional view on the line 4-4 of Fig. 2.

In Fig. 1 I have illustrated a diagrammatic layout of the apparatus, the piping, 90 pump and gear connections being arranged for convenience of illustration.

In general the apparatus comprises a spray chamber 10 into which is atomized a mixture of air and fuel supplied by the 95 multi-cylinder pump indicated in general by the numeral 11. Fuel is supplied to the pump apparatus from the heavy-oil tank H and light-oil tank L, the surplus mixture not used by the engine being returned to the 100 pumping apparatus through the pipe 12, and the oil in the mixture pumped back to the tank H through pipe 13.

The vaporizing chamber comprises a cylindrical drum shaped casing 14, at one end 105 of which is formed a pipe section 15, for insertion in the intake duct 16 of a gas engine indicated in dotted lines at 17. A passage way 18 provides communication between the pipe section 15 and the interior 19 of the 110 spray chamber. The opposite end of the drum shaped casing 14 is covered by a re-

movable head 20, in which is mounted an atomizing nozzle 21, positioned to lie in direct alignment with the passage-way 18. To throttle the size of the opening in the passage-way 18, and regulate the amount of fuel sprayed through the opening, I have provided a disk 22, mounted on the inner end of the spindle 23, which is journaled within a tubular projection 24 carried by 10 the head 20. A portion of the periphery of the disk 22 is cut away, at 25, to provide a free passage of the atomized spray of fuel from the nozzle 21 through chamber 19 into duct 18 when the rotatable valve or disk 22 15 is in the position as indicated in Fig. 4. Obviously rotation of the disk through the medium of the spindle 23 opens or closes the passage way 18 to any desired extent.

The fuel and air pumping apparatus 11 20 comprises a four cylinder pump positively gear driven by a connection 26, from a rotating part of the engine. The liquid fuel handling cylinders 27, 28, are of approximately the same size, whereas the air cylinder 29 and surplus fuel handling cylinder 30 are considerably larger. Each of the cylinders 27 and 28 is provided with an individual sump, or supply well 27', 28', into which lead the pipes 31 and 32 connected 25 respectively to the tanks L and H.

The air and surplus fuel handling cylinders 29 and 30 are provided with a common sump 33, the intake 34 of the surplus fuel handling pump extending very close to 30 the bottom of the sump, whereas the intake 35 of the air pump connects with the top of the sump. The surplus fuel handling pipe 12, heretofore referred to, is tapped into the bottom of the vaporizing chamber, 35 as at 36, and communicates at its other end 37 with the bottom of the sump 33.

Pipes 38, 39, lead respectively from the oil pumps 27, 28 to a common pipe 40, which extends up to a T 41, into which also leads 45 pipe 42, which communicates with the delivery of the air pump 29. From the opposite end of the T a short pipe 43 leads to the spray nozzle 21.

A butterfly throttle valve 43, is provided 50 in the intake 16 below the connection with the vaporizing chamber 19 and is provided with a lever 44 which is connected by means of a link 45 to the lever 46 on the outer end of the throttle spindle 23. Operation of 55 the spindle from a convenient point within the reach of the driver of the car is secured by link connection with the lever 47. From the arrangement shown in Fig. 2, it will be obvious that the throttle valve 22 is so connected with the air control throttle 43, that both will be wide open simultaneously and will be opened or closed proportionately.

A cross connecting pipe 48 joins pipes 31 and 32, and is provided with a valve 49, 60 similar valves 50 and 51 being provided re-

spectively in pipes 32 and 31 so that if desired, communication may be shut off with either one of the two tanks and the other tank will then feed to both oil pumps 27 and 28 simultaneously. Thus by cutting off 70 valve 50 and opening valve 49, light oil will be fed into both the oil pumps 27 and 28, whereas if valve 51 is closed and valve 50 opened, heavy oil will be fed into both of the pump cylinders. 75

Having described in a general way, apparatus such as may be used for carrying out my invention, it will be obvious that the pump operating in timed relation to the engine, will at all times pump an amount of 80 fuel proportional to the speed of the engine.

This amount or quantity of fuel is determined by the pump cylinders which are so designed as to supply a maximum amount for any engine speed. For further manipulation of the apparatus valves 52, 53, 54 and 60 are provided in pipes 15, 39, 38 and 42, respectively. With the apparatus operating with combined light and heavy oil, a proportional amount of both will be fed into 90 the pipe 40, and thence into the atomizing nozzle where it is mixed with the air coming through pipe 42, and projected in a jet into the aperture 18 communicating with the intake of the engine. Throttling is secured 95 by interposing in the spray or steam of fuel the disk valve 22, the surplus then being drained back to the sump 33 through pipe 12. The surplus oil flowing into sump 33 is drawn through the intake 34 into cylinder 30 and then returned through pipe 13 to the heavy oil tank. The inlet 35 for air pump 29 is positioned at the top of the sump 33 so that it will draw such gas as may separate from the mixed returned fuel and enrich the mixture. 100

Whereas I have illustrated and described a single embodiment of my invention it is obvious that various changes may be made therein without departing from the spirit 110 and scope of the appended claims.

Having described my invention, what I claim is:

1. The combination with an internal combustion engine intake duct having an aperture therein, of means for projecting a spray of liquid fuel into said aperture, and adjustable means for diverting a portion or all of the spray from passage through the aperture. 115

2. The combination with an internal combustion engine intake duct having an aperture therein, of a fuel supply, of means for projecting a spray of liquid fuel into said aperture, adjustable means for diverting a portion or all of the spray from passage through the aperture and means for returning the fluid in the diverted portion of the spray back to the supply. 125

3. Means for supplying a combustible 130

charge to an internal combustion engine, comprising an intake duct, means for projecting a spray of fuel into said duct, and means for adjusting the quantity of the spray passing into said duct without affecting the volume of the spray.

4. The combination with an internal combustion engine, of an intake duct, means for projecting a spray of fuel into said duct 10 comprising a pump having a capacity for supplying an amount of fuel at no time less than the maximum amount the engine is capable of utilizing, and means for adjusting the quantity of the spray passing into 15 said duct without affecting the volume of the spray.

5. The combination with an internal combustion engine of an intake duct, means for projecting a spray of fuel into said duct 20 comprising a pump driven by said engine and having a capacity for supplying an amount of fuel at no time less than the maximum amount the engine is capable of utilizing, and means for adjusting the 25 quantity of the spray passing into said duct without affecting the volume of the spray.

6. The combination with an internal combustion engine intake duct having an opening therein, of means comprising an atomizing nozzle for projecting a spray of liquid fuel directly into said opening, and means comprising a rotatable apertured disk interposed between said spray nozzle and opening for diverting a portion or all 25 of the spray from passage through the opening.

Copies of this patent may be obtained for five cents each, by addressing the "Commissioner of Patents, Washington, D. C."

7. The combination with an internal combustion engine intake duct having an aperture therein, of means for projecting a spray of liquid fuel into said aperture, adjustable means for diverting a portion or all of the spray from passage through the aperture, a throttle valve in said intake duct and means connecting said throttle valve and said adjustable means for operating them simultaneously.

8. In an apparatus for supplying a combustible charge to an internal combustion engine, the combination of a fuel supply, an intake duct, a spray chamber communicating with said duct, a spray nozzle in said chamber, a pumping apparatus driven from the engine and comprising a liquid fuel pumping cylinder, an air pumping cylinder, and pipes connecting the discharge of said cylinders with the said nozzle, a surplus pumping cylinder, a pipe connecting the intake of said surplus pumping cylinder with the bottom of the spray chamber, a pipe connecting the discharge of said surplus pumping cylinder with the fuel supply, and adjustable means for diverting a portion or all of the spray from passage through the aperture.

In testimony whereof I hereunto set my hand in the presence of two subscribing witnesses.
